UNITED STATES PATENT OFFICE.

THEODORE D. ROBINSON, OF LOCKPORT, NEW YORK.

WATER-RADIATOR.

1,086,403.

Specification of Letters Patent. Patented Feb. 10, 1914.

Application filed November 27, 1909. Serial No. 530,239.

To all whom it may concern:

Be it known that I, THEODORE D. ROBINSON, a citizen of the United States, residing at Lockport, in the county of Niagara and State of New York, have invented certain new and useful Improvements in Water-Radiators, of which the following is a specification.

My invention relates to radiators, but more particularly to radiators for automobiles for rapidly cooling the water passing through the water-jackets of an engine. In radiators employed for such purposes, the water enters the same in a heated and sometimes boiling condition and is discharged therefrom in a comparatively cool condition. The rapid cooling of the water by the mere passing of the same through the radiator, subjects the latter to severe strains, due to the uneven contraction and expansion of the parts. This is particularly true of a tube radiator, in which individual air-tubes are assembled in block form and united at the ends to form water-passages therebetween. My invention is applied to a radiator of this type, wherein the air-tubes are united at the ends by soldering them together, and the object of my invention is to so construct the tubes that the expansion and contraction of the same will be confined wholly to points intermediate the means of uniting them at the ends with adjoining tubes, thus relieving the soldered ends of all strain, which has heretofore been a serious objection to radiators of this type.

My invention also provides a radiator of greater efficiency, one having greatest strength at the points heretofore considered the weakest, and one which can be more economically manufactured.

To these ends the invention consists in the construction, arrangement and combination of parts to be hereinafter described and particularly pointed out in the subjoined claims.

In the accompanying drawings, forming a part of this specification,—Figure 1 is a front elevation of a radiator constructed according to my invention. Fig. 2 is a horizontal section taken on line 2—2, Fig. 1. Fig. 3 is a vertical longitudinal section through the radiator. Fig. 4 is an enlarged vertical section through a portion of the radiator taken on the line 4, Fig. 1. Fig. 5 is an enlarged detached perspective view of one of the tubes.

Referring now to the drawings in detail,

like letters or reference refer to like parts in the several figures.

The radiator comprises essentially, a casing A, and a group or block of assembled air tubes B surrounded by said casing. The casing A has an inlet chamber C at its upper end into which the heated water from the water-jacket of an engine is delivered, and an outlet-chamber D at its lower end from which the cooled water passes to the said water-jackets, as is common in radiators of this kind. The group or block of assembled tubes separates the inlet-chamber from the outlet-chamber and the water in passing from one to the other is divided into numerous streams which find their way through the spaces between the air-tubes and finally reach the outlet-chamber D. These tubes I have designated E and the spaces between the tubes F. The air-tubes E are preferably arranged in horizontal rows extending from side to side of the casing and they are staggered from top to bottom. Each tube has a continuous bead G at each end formed by gradually bulging the metal outward so as to form a gentle slope from the edge inward and a gentle slope from the point of greatest expansion inward to the normal size of the tube, the extremity being therefore retained at normal size. This results in substantially inverted U-shaped beads being formed entirely around the tube. The beads of each air-tube lie in contact with the beads of adjoining air-tubes so as to provide shallow grooves between the extremities of the tubes, whose walls gradually converge inwardly immediately from the edges of the tubes. These grooves are therefore substantially U-shaped, and in them solder H is entered to rigidly and securely unite the tubes.

In constructing the radiator, the numerous air-tubes are held in assembled condition by suitable clamps and their front and rear faces dipped into liquid solder which fills the end grooves and also covers the edges of the tubes so that the block of tubes has the appearance shown in Fig. 1. In this manner, the seams between the solder and the tubes are rendered invisible. By bringing the points of contact between the tubes at points slightly in rear of their front edges and slightly in front of their rear edges, a very rigid construction is obtained owing to the solder entering the grooves between said points of contact and the ends of the tubes. The most important feature of my

invention, however, lies in forming the beads by bulging out or expanding the metal gradually, preferably by means of curving the walls of said beads so that all sharp angles are avoided and so that under strain, due to expansion and contraction, the metal at the inner half of the beads will flex or yield. As the outer half of the walls of said beads are united in a rigid manner, only 10 the inner half will yield under strain and consequently as the metal of the tubes becomes subjected to different degrees of temperature and expands and contracts, the tubes yield only at points between the transverse centers or summits of the beads at their front and rear ends, thus relieving the joints of all strain and consequently avoiding separation or tearing away of the solder. By means of this construction, a substantially rigid wall is formed at the front and rear of the radiator between which is a region in which the metal of the tubes is free to expand and contract without straining the solder between the tubes. The 20 transverse centers or summits of the beads define the division lines between the substantially rigid front and rear walls and the expansion region, since the solder, owing to the comparatively shallow face grooves 30 and their gradual inward reduction in size, fills the spaces or grooves entirely up to the summits of the beads.

The air-tubes are made of very thin sheet copper so that the air passing therethrough 35 will act to quickly cool the numerous small streams of water passing through the water-passages F.

Having thus described my invention, what I claim is,—

40 1. A radiator comprising a plurality of assembled horizontally-disposed tubes, each tube having a bead at one end formed by gradually expanding the metal outward immediately from its edge and having the summit of its bead lying in contact with the summits of the beads of all adjoining tubes, thereby forming water passages intermediate the ends of the tubes and solder-receiving grooves between their extremities 45 and the summits of said beads, and solder in said grooves uniting said tubes and forming a rigid wall between the summits of said beads and the edges of said tubes.

50 2. A radiator comprising a plurality of

assembled tubes expanded at their ends to 55 form beads and receiving from their points of greatest expansion outward to the edges of the tubes and inward to the unexpanded intermediate body portions thereof, the beads of each tube being endless and lying in contact with those of adjoining tubes to form solder-receiving grooves having inwardly curving walls, and solder within said grooves for uniting said tubes, the inner half of all beads being free to flex when the 60 tube of which it forms part expands or contracts so that the solder in said grooves is relieved of strain.

3. A radiator comprising a plurality of 70 assembled rectangular tubes, each tube having endless beads at opposite ends formed by expanding the metal, the walls of said beads receding outward from their greatest points of expansion to the edges of the tubes and inward to the unexpanded intermediate 75 body portion, thereby forming water passages between the tubes closed at opposite ends by said beads, and solder inserted between the tubes outside of said beads at opposite ends of the tubes to form two 80 rigid walls confining the expansion and contraction of the metal forming the tubes to the regions between the points of greatest expansion of the beads at opposite ends of said tubes.

4. A radiator comprising a plurality of 85 assembled tubes having spacing-beads at opposite ends, the spacing bead of each tube lying in contact with the beads of adjoining tubes and each tube having its spacing 90 beads at the extremities formed to provide a gradually enlarged cross-sectional measurement from the edge of the tube inward and then a gradually reduced cross-sectional measurement until the normal size of the 95 tube is obtained, thus forming gradually narrowed spaces between the end edges thereof and the two points of greatest diameter, and solder filling said spaces and uniting said tubes.

100 In testimony whereof, I have affixed my signature in the presence of two subscribing witnesses.

THEODORE D. ROBINSON.
